Primary Examiner — Robert M Spear*Assistant Examiner* — Kendra L Hamilton(74) *Attorney, Agent, or Firm* — Robert M. Downey, P.A.(57) **CLAIM**

The ornamental design for a protective cover for a pacifier, as shown and described.

DESCRIPTION

FIG. 1 is a front, top perspective view of a protective cover for a pacifier showing my new design;

FIG. 2 is a front elevational view thereof;

FIG. 3 is a right side elevational view thereof;

FIG. 4 a rear elevational view thereof;

FIG. 5 is a left side elevational view thereof;

FIG. 6 is a top plan view thereof;

FIG. 7 is a bottom plan view thereof; and,

FIG. 8 is a rear, top perspective view thereof.

The broken lines shown in FIGS. 3 through 8 form no part of the claimed design.
